SHIP'S HULL

William P. Baker, Brooklyn, N. Y.

Application December 7, 1937, Serial No. 178,481

5 Claims. (Cl. 114—56)

The present invention relates to an improvement in boat hulls and has for its important advantage the provision of structural, streamlined features on the wetted surfaces of the hull, whereby to decrease pitching and squatting of the vessel when under headway.

The present hull construction, due to the contours of the wetted surfaces thereof, especially of the bow and stern, also lessen the rolling of the vessel and eliminate the necessity of providing rolling chocks or bilge keels.

Further advantages of the present construction are in the saving of power in the propulsion of the vessel, and, due to lessening of pitching, greatly reduces the tendency of the exposing and consequent racing of the propulsion means in rough seas, and, further reduces sinkage.

In other words, the present betterment of the under-water lines of the hull greatly increases the stability of the vessel when under way, or in rough seas, and reduces wave, vortex and eddy action, as well as increasing the economy, in power consumption.

A further feature of advantage herein is that the vessel moves through the water, with less turbulence or disturbance than in known types of hulls, and, due to this action, side waves and turbulences are reduced, and as the relatively moving water approaches the propellers, it moves in a substantially smooth, unbroken stream, and without undue wave disturbance, and substantially in line with the axis of the propellers.

The contour of the wetted surfaces of the stern are arranged to favor the foregoing noted water flow action, as will later be described in detail.

Further features of advantage will be apprehended as the herein description proceeds, and it will be obvious that modifications may be made in the features herein disclosed without departing from the spirit hereof, or the scope of the appended claims.

In the drawings,

Fig. 1 is a combined diagrammatic plot of the ship's curves, the right hand section showing a section of the bow end of the vessel, the left hand section showing a section of the stern end of the vessel;

Fig. 2 is a diagrammatic, reduced side view of the plot of the curves or contours of the side of the vessel;

Fig. 3 is a diagrammatic, half sectioned view of the plot of curves of the vessel, as seen from the flat bottom;

Fig. 4 is a slightly enlarged, fragmentary view

of the side of the vessel, showing the hull from the bow end to beyond the central or midship line *a—a*;

Fig. 5 is an enlarged vertical section taken on line *x—x*, Fig. 4, looking in the direction of the arrows;

Fig. 6 is an enlarged vertical sectional view taken on line *Y—Y*, Fig. 4, looking in the direction of the arrows; and

Fig. 7 is an enlarged vertical sectional view, 10 taken on the line *Z—Z*, Fig. 4, looking in the direction of the arrows.

In the diagrammatic views of Figs. 1, 2 and 3, the letter and numeral indices all correspond for like profiles at like intersections.

In Figs. 4, 5, 6 and 7, the deck *T* of the said views are cut away at about the traversing line 2, Fig. 1, right hand section.

As shown in Fig. 1, the vertical profile lines *e*, *d*, *c* and *e* of Fig. 1, right section, Fig. 2 bow section and Fig. 4 indicate that the bow *x* has a sharp, slightly concaved stem, with slightly concaved adjacent hull sides, as indicated by profile lines *e*, *d*, *c* and *b*, Fig. 1, and an amplified bulb *B* which originates at the forefoot of the stem *x* and continues in gradually varying cross section, until it passes the mid-section of the hull at line *a—a*, Fig. 4, where its contour gradually merges thereafter into the hull lines.

The nose of the bulb *B*, like the stem, is also sharp at its vertical entrant portion, as at *w*, Figs. 1, 2, 4 and 5, said entrant portion *w* originating at the stem *x*. Said sharp nose or prow of the bulb *B*, as seen in Figs. 1 and 2 forms a vertical, curved continuation *w* of the stem *x*, as it merges with the flat bottom of the hull *B'''*, which, as will be seen in Figs. 1, 2, and 4, is in a flat, continuous plane from bow to stern.

The nose of the bulb *B*, at *v*, Figs. 2 and 4 is also sharpened at the entrant edge *v*, transversely to the sharp vertical prow *x—w*, so that the transverse entrant cutting portion of the nose of the bulb *B*, at *x—v—w* is at a right angle to stem *x* and forms, with the stem *x* a cruciform-like entrant prow, the transverse cutting line being shown dotted at *v*, Fig. 1.

From beyond the cutting or entrant edges of the bulb *B*, towards the stern, the vertical thickness of the bulb may remain constant in dimension, and thus the top line of demarcation *B'* runs parallel with the flat plane of the hull bottom *B'''*, as seen in Fig. 1, shown dotted, and in Fig. 4. The line *B'*, between the top surface of the bulb *B* and the both sides *H* of the hull, may be smoothly joined by a modified curve or fillet *B'*,

best shown in Figs. 5 and 6, which line gradually merges into the bottom hull lines as it passes toward the stern, as at B'', Figs. 4 and 7.

As shown in Figs. 1 and 4, the sharp transverse, 5 entrant cutting line v starts from the curved plane of the vertical prow or stem x and is slightly and angularly sloped, or downwardly disposed, rearwardly as at v , Fig. 4, and merges from the sharp forward edge v into the rounding outer 10 forward edges F of bulb B, as at Fig. 4, this merging of lines occurring just aft of section $x-x$, Fig. 4.

The opposed, lower front faces D of the entrant portion of the bulb below cutting line v , 15 Fig. 5, are slightly concaved as at D, this concavity gradually reversing and merging with the gradually developed convex of lower bulb surfaces E-E, Fig. 6 which convex surfaces gradually merge and flatten within the plane of the flat hull 20 bottom B'', Fig. 7. The cutting line w continues past section $y-y$, Fig. 4, where it gradually merges, flattens with and loses its identity in the flat hull bottom plane B'''.

The upper, opposed front surfaces G of the 25 bulb entrant portion, as will be seen in Figs. 1, 4 and 5 are slightly convexed or upwardly crowned from the entrant edge v , as disclosed at G, and which surfaces, defined by the transverse cutting entrant edge v , gradually merge at F into 30 the rounding outer edges of the bulb as at B-B, Figs. 4, 6 and 7. The surfaces G-G and D-D are so developed that they form an angularly developed shelf-like projection from the entrant edge v to, or beyond the mid-ship line 35 $a-a$. The cutting entrant portion $v-w$ is also angularly related to the hull sides H-H near the stem x thereof as will be noted in Fig. 5.

The entrant or leading edge of the bulb is sharp, is inclined rearwardly and downwardly, 40 is concaved at its lower faces from the lower entrant cutting edge, is convexed on its upper faces from its entrant edge v , said entrant leading edge being located above the medial bulb line m' , Fig. 4, into which it merges. This 45 structure tends to part the bow water in an easy, substantially non-turbulent manner, and, with its associate sharp stem x , acts as leading, fixed vertical and horizontal bow rudders, which, without much bow turbulence, ease the 50 moving bulb and hull into the relatively on-coming water, this action tending to gradually displace the water in an easy and non-turbulent manner. The bulb is so constructed as to be of constantly changing cross section from its 55 entrant portion to its rear terminal portions where it gradually merges with the hull lines near the widest beam dimension $a-a$, amid-ship and the slight wave started by the entrant leading edges $v-w$ is rolled along and 60 away from the bulb and coacting hull sides, said water traveling in part by an easy rear-ward and side wave displacement in part to-wards the propellers of the vessel, and the pro- 65 peller, or propellers are thus operated in sub-stantially a solid body of water, thus increasing the propulsion action, and decreasing to a fa-vorable extent, the slip of the propulsion means. Due to the bulb-water action, and the flat bot- 70 tom portion of the hull, water is passed under the vessel and over and along the bulb sec-tion, and during movement of the vessel, the bite of the displaced water along the top sur-faces of the bulb stabilizes the vessel longi-tudinally, against pitching action of the hull, 75

and obviates, to a large extent the rolling ac-tion also.

The stern sections of the wetted surfaces of the hull recedes from the widest mid-ship line $a-a$, Figs. 2 and 3 by easy recessional contours 5 defined by the section lines n , r , s and t , the stern at S, Figs. 1, 2 and 3, ending in a sub-stantial sharp trailing edge below the load wa-ter line, LWL, as shown in Fig. 1, left hand section, and Figs. 2 and 3. Thus the displaced 10 water may well up from the flat bottom of the hull, and flow inwardly from the surrounding water to the hull sides to insure a solid, sub-stantially non-turbulent body of water in which the propellers operate, and further, the 15 displaced water presses against both sides of the wetted surfaces of forward divergent sec-tions of the hull and shelf-forming bulb, the action of which accomplishes the desired 20 stabilizing action of the hull.

The elongate, divergent, bulb portions B, are extended to at least the widest mid-section of the hull H, (and may extend beyond) and when under headway, through the elongate, divergent displacement thereof, as will be understood from the foregoing description, cause the hull to be gripped by the displacement water along at least half of the length of the hull, thus creating a continuous and enormous reaction against 25 pitching and rolling or squatting movements of 30 the vessel, and the bulb, being parallel with the flat bottom of the hull causes such reaction, without interposing undue resistance to the headway of the vessel.

The dead rise of bulb forward of midship sec-tion tends to raise the bow and the flow striking 35 the flat after section tends to raise the stern thereby lessening the amount of sinkage, thus effecting a saving in horsepower.

Having thus described the invention what is 40 claimed is:

1. A boat hull having approximately vertical sides, a substantially horizontal flat bottom, wide at its mid-section and tapering to stem and stern and a sharp concaved stem; each side 45 of the hull being provided forward of the mid-section along and just above the side portions of the bottom with a laterally projected convexedly rounded bulb merging with the bottom and side; each bulb becoming laterally sharper 50 as it extends forward, and terminating forwardly in a transverse entrant edge about as wide as the bulb and crossing at the forefoot of the stem; the depth of the bulb being ap-proximately less than a third of the submerged 55 depth of the hull.

2. A boat hull having a substantially flat bot-tom, wide at its mid-section and tapering to stem and stern and a sharp stem terminating at the forefoot of the stem in a short nose 60 merging with the bottom; each side of the hull being provided forward of the mid-section along and just above the side portions of the bottom with a laterally projected convexedly rounded bulb; the side of each bulb gradually becoming 65 less rounded and more sharp as the bulb ex- 70 tends forward until a sharp upwardly inclined lateral cutting edge is formed as the bulb ter-minates at the forward end in a sharp right angularly transverse entrant edge near the top 75 level of the bulb and crossing the stem at the forefoot and the upper part of the nose to form with the stem and nose a cruciformlike entrant prow; the length of each entrant edge approximating the greatest width of the bulb, 80

5 the lower surface to the rear of said edge being slightly concaved and sloping rearwardly and inwardly downwardly to merge with the convexedly rounded portion of the bulb and said bottom; the upper face of the bulb at the entrant edge being slightly upwardly convexedly around the surface of which gradually merges with the convexity of the bulb.

10 3. A boat hull having a substantially level flat bottom wide at its mid-section and gradually tapering to its stem and stern; the upper part of the wetted surfaces of the sides, being approximately vertical and receding inwardly downwardly; the stern sections of the wetted 15 surfaces of the hull gradually receding by easy recessional contours to form a substantially sharp trailing edge; the bow having a sharp slightly concaved stem slightly rearwardly and downwardly inclined to its forefoot and there merging into a sharp nose which quickly merges 20 into the flat bottom; said hull being provided forward of the mid-section along each side of the hull just above the sides of the bottom with an elongated convexedly rounded projecting 25 bulb projecting outwardly slightly from the lower part of the hull and having curved faces merging downwardly with the bottom and curving upwardly, inwardly and upwardly to form a modified fillet to merge with the side of the 30 hull; each bulb being of substantially constant vertical dimension throughout and gradually becoming less laterally projected from the side as it extends toward the mid-section and merging 35 with the side and bottom, and finally merging with the bottom and sides just aft of the mid-section.

4. A boat hull having approximately vertical sides and a substantially horizontal flat bottom, wide at its mid-section and tapering to stem and stern; the stem being sharp and rearwardly and downwardly inclined to its forefoot, merging into a short nose merging into said bottom; each side of the hull being provided at and forward of the mid-section, along and just above the sides of the bottom, with a fully submerged laterally projected convexedly rounded bulb having its lower part merging with the bottom, the bulb curving upwardly and inwardly and having a fillet merging with the side; each bulb becoming laterally sharper as it extends forward, merging into a sharp upwardly inclined lateral cutting edge portion, whereby the bulb rises at its forward end, said

5 cutting edge portion terminating forwardly in a transverse entrant edge about as wide as the bulb and near the top level of the bulb and crossing the stem at the nose to form cross-shaped entrant prow; the lower surface at said entrant edge being concaved, sloping rearwardly inwardly downwardly to merge with rounded portion of the bulb and said bottom; the upper surface of said entrant edge portion at the rise being slightly convexed and gradually merging with the bulb; the rise and lower concavity of the bulb at the forward end and the flat bottom cooperating to lessen sinking, thereby decreasing necessary power; said entrant edge of the bulb at the forefoot being sharp both vertically and laterally making easy entrance of the bulb in a non-turbulent manner and lessening pounding.

10 5. A boat hull having approximately vertical sides and a substantially horizontal flat 20 bottom, wide at its mid-section and tapering to the stern and sharply to the stem; each side of the hull being provided forward of the mid-section along and just above the sides of the bottom with a laterally projected convexedly 25 rounded bulb having its lower part merging with the bottom, the bulb curving upwardly inwardly and having a fillet merging with the side; each bulb becoming laterally sharper as it extends forward, terminating forwardly at the 30 stem in a transverse entrant edge about as wide as the bulb; each bulb being of substantially constant depth from top to bottom thereof, of approximately less than a third of the 35 submerged depth, and having widest projection well forward and gradually decreasing rearwardly and merging with the hull after the mid-section, thereby tending to pump water aft where it is needed, the water passing over the bulb meeting water passing under the flat bottom of the hull aft of midship, straiting out the 40 flow to meet the propeller in a horizontal line making propeller thrust more effective; the top side of each bulb gradually forwardly increasing in width to approximately half the depth of the 45 bulb and forming an approximate right angle with the side, restraining the water from running transversely under the hull, thereby damping rolling; the length and width of said top side of the bulb from mid-section to stern damping 50 rise and fall of the boat longitudinally.

WILLIAM P. BAKER.
